HAIR ROLLER

Nathan L. Solomon, P.O. Box 550, Englewood, N.J.

Filed June 17, 1964, Ser. No. 80,447

Term of patent 14 years

(Cl. D86—10)

FIG. 2

FIG. 1 is a perspective view of a hair roller showing my new design; and

FIG. 2 is an end elevation view thereof, portions thereof being shown broken away for purposes of illustration.

The hair roller shown has a characteristic feature, the inner toothed serpentine longitudinal ribs intersected by a continuous helical rib.

I claim:

The ornamental design for a hair roller, as shown and described.
